UNITED STATES PATENT OFFICE.

JOHN M. RUTLEDGE, OF MIDVALE, OHIO.

PIPE AND ROD WRENCH.

1,123,598.

Specification of Letters Patent.

Patented Jan. 5, 1915.

Application filed May 5, 1914. Serial No. 836,482.

To all whom it may concern:

Be it known that I, JOHN M. RUTLEDGE, citizen of the United States, residing at Midvale, in the county of Tuscarawas and State of Ohio, have invented certain new and useful Improvements in Pipe and Rod Wrenches, of which the following is a specification.

This invention relates to improvements 10 in pipe and rod wrenches, and has for one of its objects to provide a simply constructed device which is readily applicable to pipes and rods of varying sizes, and which will firmly grip the same and prevent it 15 from rotation thereon.

Another object of the invention is to provide a simply constructed device which may be applied to rods or pipes of varying sizes and which may be applied to the rod or 20 pipe at otherwise inaccessible locations.

With these and other objects in view the invention consists in certain novel features of construction as hereinafter shown and described and then specifically pointed out in 25 the claims; and in the drawings illustrative of the preferred embodiment of the invention Figure 1 is a side elevation of the improved implement applied to a section of a pipe. Fig. 2 is a front elevation of the 30 parts shown in Fig. 1.

Corresponding and like parts are referred to in the following description and indicated in all the views of the drawings by the same reference characters.

35 The improved device comprises a stock or handle 10 preferably tubular, and formed with spaced cheek portions 11-12 at one end. The stock is preferably constructed from a section of piping, the cheek portions 11-12 being formed integral therewith as 40 represented.

Pivoted at 13 between the cheek portions 11-12 is a head member 14, the head member being considerably less in thickness than 45 the distance between the cheek members 11-12 and held centrally between the same by spacer members 15. In its outer edge the head member 14 is formed with a concaved recess having gripping teeth 16 as 50 shown. One edge of the member 14 is formed eccentric to the pivot 13 and the eccentric edge provided with ratchet teeth 17. Pivoted at 18-19 to the cheek members 11-12 and between the cheek members 55 and the head member 14 are arms 20-21. The arms 20-21 are coupled near

their outer ends by a pin 22 which thus holds the arms in spaced relation. At their outer ends the arms 20-21 are provided with outwardly opening hooks 23-24. The 60 arms 20-21 are thus free to swing upon their pivots 18-19 and operate in close proximity to the side faces of the member 14.

A flexible member 25 is formed of a plurality of links pivotally united at 26, the pivot 26 of the innermost link being utilized to unite one end of the flexible member to the head 14 as shown. The links of the flexible member 25 are arranged to pass between 70 the outer ends of the arms 20-21, and the pivots 26 of the links are extended at their ends to engage in the hooks 23-24. Any required number of the links may be employed, and each link is adapted to be coupled by 75 the pivots 26 with the arms 20-21 as represented in Figs. 1 and 2. By this means the improved wrench may be adapted to fit rods or pipes of various sizes by simply adjusting the flexible member 25 relative to 80 the arms 20-21, as hereafter more fully explained.

Pivoted at 27 within the tubular stock 10 is a pawl 28 adapted to engage with the ratchet teeth 17 one at a time. The pawl 28 85 is extended into the interior of the stock 10 as represented at 29, and formed with an outwardly directed terminal 30 which extends through an opening in the stock 10. A spring 31 is arranged to maintain the bill of 90 the pawl 28 yieldably in engagement with the ratchet teeth 17, but will yield when pressure is applied to the terminal 30 to force the pawl from engagement with the ratchet teeth. The stock 10 is preferably 95 provided with a hollow or recess 32 where the aperture for the terminal 30 is located, so that the movement of the pawl may be increased without increasing the size of the stock 10, and likewise preventing undue 100 prominence to the member 30.

The parts are all constructed of metal, preferably steel with the member 14 and its teeth 16 hardened to withstand the strain to which they will be subjected.

With a device thus constructed, it will be obvious, that by releasing the flexible member 25-26 from the arms 20-21 and actuating the pawl 28-29 to release the head 14 and moving the latter upon its pivot 13 until 110 the pawl is in engagement with the ratchet tooth 17 which is nearest to the concaved

toothed edge 16, the improved device may be applied to a rod or pipe by placing the gripping edge 16 of the member 14 against the pipe or rod at one side and then passing 5 the flexible member 25—26 around the pipe and drawing it as closely as possible and engaging the nearest pin 26 with the hooks 23—24. Then, by moving the stock 10 in a direction to cause the pawl 28 to pass over 10 the inclined sides of the ratchet teeth 17 the head 14 will firmly grip the rod or pipe and effectually lock the wrench device to the rod and prevent it from rotating thereon, thus enabling the rod or pipe to be rotated by 15 actuating the wrench.

The improved device is simple in construction, can be strongly and inexpensively constructed and in varying sizes to suit rods and clamps of correspondingly varying 20 sizes.

Having thus described the invention, what is claimed as new is:

1. A wrench comprising a stock, a head member mounted to swing in said stock and 25 having one edge eccentric to its pivot and another edge concaved and provided with gripping teeth, a flexible member swinging at one end from said head, means for adjustably connecting said flexible member relative to said stock, and means for holding 30 said swinging head in any adjusted position.

2. A wrench comprising a stock, a head member mounted to swing in said stock and

having one edge eccentric to its pivot and 35 provided with ratchet teeth and another edge concaved and provided with gripping teeth, a flexible member swinging at one end from said head means for adjustably connecting said flexible member relative to said stock, and a manually actuated pawl engaging 40 said ratchet teeth.

3. A wrench comprising a stock, a head member mounted to swing in said stock and 45 having one edge eccentric to its pivot and another edge concaved and provided with gripping teeth, a flexible member swinging at one end from said head member, an arm 50 swinging from said stock, and means for adjustably connecting said flexible member to said arm, and means for holding said swinging head in any adjusted position.

4. In a wrench of the class described, a stock having cheek members spaced apart, a head member pivoted between said cheek members and having gripping teeth in one edge, an arm pivoted in said stock, a flexible member adapted to be adjustably and detachably engaged in said arm, and means 55 for holding said swinging head in any adjusted position.

In testimony whereof I affix my signature in presence of two witnesses.

JOHN M. RUTLEDGE. [L.S.]
